HAND SOAP

Jerónimo Diaz Compain, Central Senado, Cuba

No Drawing. Application August 20, 1941,
Serial No. 407,647

2 Claims. (Cl. 252—131)

This invention relates to manufacture of hand soap; and it includes a soap which is generally useful for cleaning the grimy hands of mechanics, etc., as well as for removing grease and dirt from other surfaces contaminated therewith, said soap comprising finely divided ashes derived from the combustion of sugar cane bagasse, one of the conventional household soaps and usually sufficient water to form a paste. The invention also includes a method of making said hand soap which comprises heating a mixture of water and soap to substantially the boiling point, adding finely divided ashes of bagasse and stirring while cooling and solidifying; all as more fully hereinafter set forth and as claimed.

A large variety of hand soaps have been suggested in the art. These soaps in general include various abrasives such as finely divided sand, diatomaceous earth or the like together with an ordinary soap and water. It has also been proposed to include in such compositions wood ashes, the ashes of rice husks and the like. These compositions, while successfully removing grease and dirt, are not satisfactory for the long continued use owing to the fact that their high alkali content, derived from the ashes as well as from the soap, makes the compositions too harsh, while the abrasive tends to scratch the hands. With the continued use of such preparations the finger nails become brittle and the hands hard and full of fine scratches in which dirt tends to collect.

I have found that the ashes of bagasse, derived from the combustion of sugar cane, form a highly superior abrasive for inclusion in hand soaps which are free from the disadvantages mentioned. When these ashes in finely divided form are mixed with an ordinary laundry or household soap and sufficient water to form a paste, a hand soap is produced which can be used over long periods of time without injury to the most sensitive hands. In fact the use of this soap tends to keep the hands soft and the finger nails pliable. While the preparation feels somewhat gritty, it does not scratch the hands.

The cause for this unexpected result is not evident but I attribute the lack of harshness to the fact that the silica present in the bagasse ash is in reactive form, probably forming a silicate gel with the alkali of the soap or at least tending to buffer the same and to reduce its alkalinity. The bagasse ash itself has a low free alkali content. The ash particles are apparently softer than most if not all of the abrasives formerly used in hand soaps and this appears to account for the fact that the hands are not scratched by the use of my

soap, even over long periods of time. Most of the abrasive particles of bagasse ash can be crushed between the fingers, much like the particles of an aqueous silica gel which has been allowed to dehydrate somewhat. Part of the ashes dissolve during use which also helps to explain why they do not scratch the hands. But whatever the true explanation may be, the facts remain as stated.

The composition of the ash used in the present invention is approximately as follows:

	Per cent
SiO ₂	84.59
Al ₂ O ₃	.57
Fe ₂ O ₃	.68
TiO ₂	.06
MnO	.13
P ₂ O ₅	2.04
CaO	4.68
MgO	2.85
K ₂ O	3.79
Na ₂ O	.61

I have found that, when bagasse is burned in the usual furnace of a sugar factory, while containing its usual water content of approximately 50% by weight, two types of ash are produced. One of these has a specific gravity which is substantially lower than the other and tends to cling to the walls of the furnace, while the heavier portion tends to form in large clinkers in the furnace. The lighter portion is particularly advantageous in the present invention while the heavier portion forms a soap abrasive which is usually too sharp to make a good soap. In the preferred embodiment of my invention, therefore, I separate the lighter portion of the bagasse ash from the heavier portion and use the lighter portion only.

Separation of the lighter ash can be accomplished in various ways. A very simple way is to collect the ash which clings to the walls of the furnace. Bagasse furnaces usually require cleaning once a day and a substantial portion of the ash clings to the furnace walls. Most of this light ash drops from the walls during the cleaning operation. The heavier ash in the bottom of the furnace may be shoveled out and discarded while the portion removed from the walls can be recovered for use in my process.

The soap employed in combination with the bagasse ash can be of any ordinary variety, such as the usual household or laundry soap. In the better grades of my product castile soap can be employed and it is also possible to employ potash soaps, if desired.

The proportions of bagasse ash to soap and to water which are employed in my hand soap can be varied widely. I usually prefer to produce a product in the form of a paste which requires a water content of at least about 50% by weight. If the soap is to be packaged in collapsible tubes a somewhat higher content of water is required amounting in some cases to 75%. But even when this proportion of water is employed the preparation is sufficiently stable so that no segregation of ingredients takes place. If desired, my soap may be formed in cakes having a water content of 25% or less, in which case the inclusion of a small amount of glycerine or the like is advantageous to prevent the soap from drying out. A perfume may be added if desired. The ratio of soap to ashes to be employed depends upon the grade of soap to be manufactured. For the cheaper grades of mechanic's soap I usually employ a larger proportion of ashes than of soap, the more expensive grades the proportion of soap can be increased to a point where the ratio of ashes to soap becomes about 1:2.

The bagasse ashes should be present in the soap in finely divided form. This is accomplished by grinding or crushing the ashes followed by screening them. I prefer to employ the fraction which passes a screen having from 20 to 70 mesh per inch but for the cheaper grades particle sizes up to 15 mesh can be used.

The soap of the present invention can be produced at a low cost for the reason that bagasse ash has heretofore been considered a waste product. The cost of grinding or crushing the ash followed by screening is low and the step of compounding the soap with the ashes and water is likewise small.

The compounding step is advantageously conducted by introducing the calculated quantity of soap into the water at substantially its boiling point. The soap quickly dissolves and then the ashes can be stirred in. During cooling the stirring must be continued until the mass thickens to such an extent that the ashes no longer tend to settle. Since the ashes have a low specific gravity they have but little tendency to segregate and hence my products are stable even though they may be relatively fluid.

A satisfactory formula for my hand soap is as follows:

	Per cent
Water	50
Soap (yellow laundry soap)	18
Bagasse ashes (30 mesh)	32

5 The best proportions to be used in making a hand soap in paste form are about 50 to 60% by weight of water, 15 to 20% of water soluble soap and 20 to 35% of finely sifted bagasse ashes.

10 While I have described what I consider to be the most advantageous embodiments of my invention, it is evident that various specific details which have been mentioned can be varied substantially without departing from the purview of this invention. It is evident, for example, that the bagasse ash, soap and water can be compounded in any desired manner. It is possible for example to mix the ash and the soap in dry form and then to add the water, heating until the soap is dissolved. The finished product can be packaged in any desired form, the water content being varied to suit. Any of the usual types of soap can be employed and it is even possible to employ soap substitutes in compositions which are sufficiently viscous to prevent the ashes from settling. Other modifications of this invention which fall within the scope of the following claims will be immediately evident to those skilled in this art.

15 20 25 30 What I claim is:

1. A hand soap comprising a water-soluble soap and bagasse ashes in proportions ranging from about 1:2 to 2:1; said bagasse ashes being in finely divided form, having an alkali metal oxide content of about 4.4 per cent by weight and being composed of a lighter fraction which separates from a heavier fraction of ash upon burning bagasse in a furnace.

2. A hand soap in paste form comprising about 40 45 50 to 60 per cent by weight of water, about 15 to 20 per cent by weight of a water soluble soap and 20 to 35 per cent by weight of bagasse ashes having an alkali metal oxide content of the order of 4.4 per cent by weight and being composed of a lighter fraction which separates from a heavier fraction of ash upon burning bagasse in a furnace.

JERÓNIMO DIAZ COMPAIN.
